REFRIGERATING APPARATUS

George F. Woelfel, Madison, Fla., assignor to The Commercial Cleaning Corporation, Jacksonville, Fla., a corporation of Florida

Application January 10, 1929, Serial No. 331,678
Renewed November 20, 1934

13 Claims. (Cl. 62—127)

This invention relates to refrigerating apparatus, and more particularly to a flow restrictor or orifice for use in connection with refrigerating systems.

5 Orifices, as is well known, are employed for the purpose of separating the high and low sides of such systems and at present are of two general types, one in which the orifice is a simple one and the other in which the orifice is in the form of a tube of the desired dimensions. Of the two types, the latter is the most practical in small refrigerating systems, for it permits, to a certain extent, measurement of the rate of flow from the high to the low side and due to the length of the tube, wear does not have such a marked effect upon the amount of refrigerant which is passed. Such tubes, however, where of the usual construction, are subject to rapid deterioration, are practically impossible to clean if they become 10 clogged and with the small size of the orifice provided, are difficult and costly to produce. An important object of this invention is to produce an orifice for use in such situations, which is so constructed that it may be readily cleansed, may be very readily and cheaply produced, and may be readily associated with screens to prevent clogging thereof.

20 A further object of the invention is to produce a device of this character which may, when desired, be very readily combined with a receiver into which the condenser of the system discharges.

25 These and other objects I attain by the construction shown in the accompanying drawings, wherein for the purpose of illustration is shown a preferred embodiment of my invention and wherein:—

Figure 1 is a semi-diagrammatic side elevation of refrigerating apparatus embodying an orifice constructed in accordance with my invention;

Figure 2 is a view partially in longitudinal section through one type of orifice;

Figure 3 is an enlarged sectional view thereof;

Figure 4 is a view similar to that of Figure 2 showing a modified form of orifice;

Figure 5 is a view in end-elevation of the inner element of the orifice, and

Figure 6 is a perspective view of this orifice element.

Referring now more particularly to the drawings, the numerals 10 and 11 designate telescopically engaged cup-shaped elements so constructed that the outer faces of the side and end walls 12 and 13 of the inner element have a close

fit against the inner faces of the side and end walls 14 and 15 of the outer element. The inner element is provided in its periphery with a spiral V-shaped groove 16 which is extremely acute so that it is of greater depth than width.

5 One end of this groove communicates with a longitudinally extending groove 17 opening through the outer face of the end wall 13 where it communicates with a radial groove 18 formed in such wall and terminating at the center thereof at a pit 19 formed by spotting with a drill. This pit centrally aligns with an outlet opening 20 formed in the center of the end wall 15 of the outer member. The opposite end of the groove communicates with the interior of the 15 inner member through an orifice 21.

The inner member 11 is of less depth than the socket of the outer member and against the end of the side wall of the inner member and within the outer member are seated a plurality of lead 20 separator rings 22 which are alternated with screens 23, 24 and 25 which are of increasing mesh size as they recede from the inner member. The end of the side wall of the outer member is offset outwardly, as at 26, providing in- 25 teriorly a seat 27 for a combined packer and separator 28, which clamps the edges of the screen 25 and likewise serves as a packing element for the seal of the inner end of the outer member 10. As a convenient means of attaching this seal, 30 hereinafter more specifically to be referred to, the outer wall at the offset portion is threaded, as at 29.

The seal or closure referred to actually provides a means for conducting the condensed refrigerant to the orifice and may be in any one of a number of forms. The forms thereof are herein illustrated and in that shown in Figures 1 and 2, the seal comprises a receiver or chamber 30 communicating directly with a condenser 31 40 and of greater capacity than the inner member 11 to contain a considerable quantity of the condensed refrigerant received from the condenser.

This chamber has an open end 32 which is closed by the structure hereinbefore recited. In 45 Figure 4, the seal is simply in the form of a cap or plate 33 centrally provided with a threaded opening permitting connection thereto of a condenser pipe or of a pipe leading from the condenser. In a structure of either character, where 50 the orifice is located at a point remote to the low side or actual refrigerating unit of the system, a very fine pipe 34 is employed to conduct refrigerant to such low side.

It will be obvious that a device of this char- 55

acter has all of the advantages of the tube and simple orifice and additionally has the advantage over the tube structure in that, in event of clogging, it may be very readily cleaned, as it may readily have associated therewith screens, reducing the chances of clogging to a minimum. By forming the groove so that it is deep and narrow, the frictional resistance to passage of fluid therethrough is materially increased, so that the size 10 of this groove may be made greater than would ordinarily be possible without passing too great an amount of the fluid.

Since the construction hereinbefore set forth is capable of a certain range of change and modification without materially departing from the spirit of the invention, I do not limit myself to such specific structure except as hereinafter claimed.

I claim:—

20. 1. An expansion device for refrigerating apparatus comprising telescopic cup-shaped members, one wall of one member having a groove cooperating with the opposite wall of the other member to provide a passageway, a closure for the mouth of the outer member, openings in the outer member and closure communicating with opposite ends of the passageway, the inner member being of less depth than the outer member, separator rings seated upon the end of the side wall of the inner member and clamped thereagainst by said closure, and screens having their edges inserted between adjacent separators.
25. 2. An expansion device for refrigerating apparatus comprising telescopic cup-shaped members, one wall of one member having a groove cooperating with the opposite wall of the other member to provide a passageway, a closure for the mouth of the outer member, openings in the outer member and closure communicating with opposite ends of the passageway, the inner member being of less depth than the outer member, separator rings seated upon the end of the side wall of the inner member and clamped thereagainst by said closure, and screens having their edges inserted between adjacent separators, said closure comprising a receiver for the discharge from the condenser.
30. 3. An expansion device for refrigerating apparatus, comprising a cup-shaped member having an outlet opening in a wall thereof, a second cup-shaped member located in said first member, the side wall of one of said members having a spiral groove cooperating with the side wall of the other of said members to provide a spiral passageway communicating at one end with said outlet opening and at the other end with the interior of said second member, and means closing the mouths of said members and having an inlet opening connecting with the interior of said second member.
35. 4. An expansion device for refrigerating apparatus, comprising a cup-shaped member having an outlet opening in the end wall thereof, a second cup-shaped member located in said first member, the side wall of one of said members having a spiral groove cooperating with the side wall of the other of said members to provide a spiral passageway, the end wall of one of said members being provided with a radial groove establishing communication between one end of said spiral passageway and said outlet opening, said second member being provided in the side wall thereof with an opening establishing communication between the other end of said spiral passageway and the interior of this member, and

means closing the mouths of said members and having an inlet opening communicating with the interior of said second member.

5. An expansion device for refrigerating apparatus, comprising a cup-shaped member having an outlet opening in the end wall thereof, a second cup-shaped member located in said first member, said second member being provided in its side wall with a spiral groove cooperating with the side wall of the other of said members to provide a spiral passageway, said second member being provided in its end wall with a radial groove establishing communication between one end of said passageway and said outlet opening and said second member being provided in its side wall with an orifice establishing communication between the other end of said passageway and the interior of this member, and means closing the mouths of said member and having an outlet opening communicating with the interior of said second member.

6. An expansion device for refrigerating apparatus, comprising a cup-shaped member having an outlet opening in a wall thereof, a second cup-shaped member located in said first member, one of said members being provided in a wall thereof with a spiral groove cooperating with the opposing wall of the other member to provide a passageway communicating with the interior of said second member and with said outlet opening, and means removably secured to said outer member for closing the mouths of said members and securing said second member in place and provided with an inlet opening communicating with the interior of said second member.

7. An expansion device for refrigerating apparatus, comprising a cup-shaped member having an outlet opening in a wall thereof, a second cup-shaped member located in said first member, one of said members being provided in a wall thereof with a spiral groove cooperating with the opposing wall of the other member to provide a passageway communicating with the interior of said second member and with said outlet opening, said second member being shorter than said first member, a screen located in said first member across the mouth of said second member, and means for closing the mouth of said first member and securing said second member and screen in place and provided with an opening communicating with the interior of said second member through the screen.

8. An expansion device, comprising two bodies having opposed contacting faces, one of said faces having a spiral groove therein, the opposing face of the other body being smooth throughout and forming with said groove a spiral passage, means securing said bodies together, inlet means communicating with one end of said passage, and outlet means communicating with the other end of said passage.

9. An expansion device, comprising two bodies having opposed contacting faces, one of said faces having a spiral groove therein, the opposing face of the other body being smooth throughout and forming with said groove a spiral passage, a member threadedly coupled with one of said bodies and securing the two bodies together, said member having an inlet communicating with one end of the passage, and an outlet for the other end of the passage.

10. An expansion device, comprising two bodies having opposed contacting faces, one of said faces having a spiral groove therein, the opposing face of the other body being smooth throughout and forming with said groove a spiral passage, a

member threadedly coupled with one of said bodies and securing the bodies together, said member having an inlet, an inlet for one end of said passage in communication with the inlet of said member, a screen interposed between said inlets, and an outlet for the other end of the passage.

11. An expansion device, comprising two circular bodies having opposed contacting surfaces, one of said surfaces having a groove therein, the opposing face of the other body being smooth throughout and overlying and forming with said groove a relatively long passage, means securing the two bodies together, means forming an outlet for one end of said passage, and means providing an inlet for the other end of the passage.

12. An expansion device, comprising two circular bodies having opposed contacting surfaces, one of said surfaces having a spiral groove therein, the opposing surface of the other body being smooth throughout and forming with said groove a spiral passage, the body having the spiral groove therein having a central opening which is in communication with one end of the passage, a member detachably connected with the said other

body and covering the central opening of the groove carrying body, said member having means for the coupling of a tube therewith, and means for coupling a tube with the said other body for communication with the other end of the spiral passage.

13. An expansion device, comprising two circular bodies having opposed contacting surfaces, one of said surfaces having a spiral groove therein, the opposing surface of the other body being smooth throughout and forming with said groove a spiral passage, the body having the spiral groove therein having a central opening which is in communication with one end of the passage, a member detachably connected with the said other body and covering the central opening of the groove carrying body, said member having means for the coupling of a tube therewith, means for coupling a tube with the said other body or communication with the other end of the spiral passage, and a screen interposed between the said member and the grooved body and secured in position over the said central opening of the grooved body by the said member.

CERTIFICATE OF CORRECTION.

Patent No. 2,018,589.

October 22, 1935.

GEORGE F. WOELFEL.

It is hereby certified that the name of the assignee in the above numbered patent was erroneously written and printed as "The Commercial Cleaning Corporation" whereas said name should have been written and printed as The Commercial Clearing Corporation, as shown by the records of assignments in this office; and that the said Letters Patent should be read with this correction therein that the same may conform to the record of the case in the Patent Office.

Signed and sealed this 26th day of November, A. D. 1935.

Leslie Frazer
